UNITED STATES PATENT OFFICE.

IRVEN J. ROBERTS, OF PHILADELPHIA, PENNSYLVANIA.

BASE-BALL GAME APPARATUS.

No. 863,758.

Specification of Letters Patent.

Patented Aug. 20, 1907.

Application filed May 28, 1907. Serial No. 376,108.

To all whom it may concern:

Be it known that I, IRVEN J. ROBERTS, a citizen of the United States, and a resident of the city and county of Philadelphia, State of Pennsylvania, have invented 5 certain new and useful Improvements in Base-Ball Game Apparatus, of which the following is a full, clear, and exact description, reference being had to the accompanying drawings, of which—

Figure 1 is a plan view of the portion of my apparatus upon which the successive plays are made and indicated. Fig. 2 is a plan view of a portion of the apparatus (in this instance, the lid of the box containing the other portion shown in Fig. 1), upon which is shown a base-ball field together with pins indicating, 15 the different positions of the players. Fig. 3 is a section on the line $x-x$, Fig. 1, through the box and rotating disk showing the indicator bar with its movable pointer in elevation. Fig. 4 is a medial section through the indicator bar and movable pointer. Fig. 5 is a 20 perspective of the movable pointer detached. Fig. 6 is a perspective of one of the pins representing the players.

The object of this invention is to provide an apparatus with which the game of base-ball may be played, 25 and to this end the invention consists primarily, in the combination, with a disk of an indicator in suitable juxtaposition and radially extending with relation to said disk, and which disk is rotatable with respect to said indicator, the indicator being divided into portions corresponding with the various conditions of men on bases that may occur in a base-ball game; and the disk is divided into circular portions by concentric 30 circles; which circular portions are in line respectively with the divisions of the indicator, and which circular portions are divided radially into sections in which are indicated various plays that may be made in the game. Mounted upon the indicator is a movable 35 pointer which may be brought opposite the corresponding circular divisions of the disk, for a purpose 40 hereinafter appearing.

The invention further consists in certain details and combinations hereinafter pointed out.

In the drawings, 1 is a box or support having mounted therein, upon a journal, 2, a horizontal disk, 3, which 45 underlies a radial indicator bar, 4, extending from the side of said box, or rather, in this instance, from a shelf or plate, 5, secured to said box, as seen in Figs. 1 and 3. The radial indicator bar is, as seen in Fig. 1, divided by horizontal lines into divisions marked respectively, 50 "0—1, 12—123—13—3—32—2", which divisions correspond with the various positions of men on bases in a base-ball game. For instance, "0" means no one on base, whereas "123" means all the bases are full, &c.

The upper surface of the disk, 3, is closely contiguous 55 to the lower surface of the indicator bar, 4, and is divided into circular divisions by concentric circles, 6,

as seen in Fig. 1; said circular divisions corresponding with and being in line respectively with the divisions of the indicator bar, 4. Said circular portions are divided by radial lines, 7, into divisions or sections of 60 such number (40 in the present instance), as may be necessary to afford indications for the different plays in the game to be played thereon, as hereinafter set forth. Each of the said divisions of said circular portions is provided with characters or letters indicating 65 plays in the game of base-ball, as shown in Fig. 1. The various plays are so distributed through said divisions that substantially any play that may occur in the game of base-ball may also occur in the use of my apparatus.

I have shown on the disk illustrated in the drawings, various arbitrary characters having meanings in accordance with the following key, to wit:—

A. B. Attempt bunt, counts a strike. Three strikes and out.

A. D. S. Attempt double steal, out stealing from 75 3rd. home, safe at 2nd. from 1st., a strike to the batter. Ball thrown from pitcher to catcher, to 2nd., & home.

B. Bunt, batter to 1st, runners advance a base.

Blk. Balk, batter to 1st, runners advance a base. 80

B. B. Block ball, ball handled by an outsider, due to a wild throw of a batted ground ball to outfield, batter to 2nd, runners advance two bases.

B. H. Base hit, batter and runners advance as many bases as shown, thus 1 B. H. 2 B. H. 3 B. H. 85

B. O. Batting out of order, batter out, balls and strikes called charged to the proper batsman following.

C. O. B. Caught off base, runner out at base shown, caught off by pitcher or catcher as shown by No. If 90 by catcher, charge ball to batter.

D. P. Double play, due to ground hit ball, runners out advancing on force to bases shown by No.

D. S. Double steal, a strike to batter, safe stealing to 2nd from first, scoring on steal home from 3rd. Ball 95 thrown from pitcher to catcher, to 2nd and home too late to make an out.

F. C. Fair catch, fly hit caught out, batter out.

F. C. Foul catch, foul hit caught out, batter out.

F. S. Foul strike, batter out for batting out of position. 100

F. T. Foul tip, caught direct from bat, a strike.

F. O. R. Fielder obstructing runner, a position shown, runner entitled to base to which he was advancing.

G. H. F. Ground hit fumbled, batter to 1st, runners advance if forced.

G. H. O. Ground hit out, runner or batter out at base shown.

H. P. B. Hit by pitched ball, batter to first others 110 advance if forced.

H. R. Home run, runners and batter all score.

- I. F. Infield fly, batter out, if two are out ball is played also making an out with side out.
- I. W. B. Interfering with batter, batter to 1st, runners advance if forced.
- 5 I. W. C. Interfering with catcher, batter out.
- M. F. B. Muffed fair ball, batter to 1st, runners advance if forced.
- M. F. Muffed foul, a strike unless two strikes have been called; if two strikes have already been called, 10 spin wheel for another play.
- M. S. Muffed strike, counts a strike, if two strikes have already been called and 1st is not occupied batter gets 1st on catcher's error; if 1st is occupied and two strikes have been called, the batter is out; if two are 15 already out and 1st is occupied the catcher recovers the ball and makes the out, side out.
- M. T. Muffed throw, ball thrown to put out a steal, runner safe on baseman's error at base shown, counts a strike to the batter.
- 20 O. Ball, counts a ball for batter, four balls entitles batter to first, runners advance if forced.
- O. S. H. Out stealing home, on fly catch to outfield, runner from 3rd trying to score on the out but was thrown out by fielder shown; others advance a base.
- 25 P. B. Pass ball, runners advance a base, ball for batter.
- R. H. B. Runner hit by batted ball, runner out running to base shown, batter to 1st, others advance if forced.
- 30 R. O. F. Runner obstructing fielder, at position shown, runner out, due to his preventing a fielder in handling a ground hit, batter to 1st, others advance if forced.
- R. O. L. Running off the line, runner out, a two 35 base hit for batter, runner from 2nd trying to score on the hit ran off the line and failed to touch 3rd; others advance two bases.
- S. Strike, three strikes batter out.
- S. A. H. Struck attempting a hit, a strike, if third 40 strike batter is out.
- S. B. Stolen base, runner safe to base shown, strike to the batter which permitted the steal.
- S. H. Sacrifice hit, when no one or one is out runners advance a base, batter out; if two out, side.out.
- 45 S. F. C. Steal on a fair catch, batter out, runner from 3rd scores on the out unless two out, then side out; others advance if side not out.
- T. P. Triple play, runners out at bases shown, 3 out, a ground hit to fielder causing a force.
- 50 T. O. Thrown out, trying to steal base shown, a ball for the batter.
- U. S. F. Umpire struck fair, hit by batted ball on fair ground, batter to 1st, others advance if forced.
- 55 W. P. Wild pitch, runners advance a base, a ball for the batter.
- W. T. C. Wild throw by catcher, to 2nd to prevent a steal, runner safe at 2nd., a strike for batter.
- W. T. F. Wild throw by fielder, a hot drive to outfield player makes wild throw to prevent a two base 60 hit, batter to 2nd, others advance two bases.
- The lid, 1^a, of the box is provided with the representation of a base-ball field having holes, 8^a, therein, in which are adapted to be inserted pins, A, corresponding with the players in the field, and the players at 65 the bat. The pins, numbered from 1 to 9, inclusive on

said Fig. 2, indicate the players in the field in their various positions, and the pin marked 10, represents the player at the bat.

Slidably mounted upon the indicator bar, is a sliding piece, 11, having an opening through its upper 70 surface which may be brought over any one of the divisions of the said bar, and having, extending therefrom, a point to come opposite any one of the circular divisions of the disk.

For convenience in keeping the score, I provide the 75 shelf or plate, 5, at each corner, with dials, 12 and 13, each of which is provided with a pair of rotatable pointers, 14, 15, and 16, 17. One of the dials, 13, has indicated thereon numerals 0, 1, 2, 3, indicating strikes, and by bringing the corresponding pointer, 16, 80 opposite any one of said numerals, indicates the number of strikes made by the batter. Said dial, 13, is similarly provided with numerals indicating the number of balls passed by the batter, which may be similarly designated by the pointer, 17. The other dial, 85 12, is similarly provided with indications for the outs and runs which may be designated respectively by the positions of the pointers, 14 and 15. On said shelf or plate, 5, intermediate said dials, is an indicator, 18, divided into rectangles, upon which may be written 90 the total score by innings.

When the apparatus is not being used, the pins, A, are removed from the holes and placed in the triangular compartments, 19, in two corners of the box, and the lid, 1^a is then put on the box, thus closing the same. 95

When it is desired to play the game, the nine pins representing the players in the field (which pins would usually be of a different color from that of the other set of pins) are placed in the field in the various positions indicated in Fig. 2, by the numerals 1—9 inclusive. The pins representing the players on the side at the bat are placed in the holes, 8^a, representing the bench, except the pin 10 representing the player who is at the bat, which is placed opposite the home plate, as seen in Fig. 2. The sliding piece or indicator, 11, 100 is moved to the position over the "0" division of the indicator bar, and the playing is ready to be begun.

The disk, 3, is spun by means of the knob, 20, and when it comes to rest the section of the outer circular division of the disk, which lies beneath the point of the indicator piece, 11, indicates the play that has been made, in accordance with the key hereinbefore set forth. For instance, should the disk stop at a point that would bring the section marked, 2 BH, under the point of the indicator, it means that the player at the bat has made a two base hit; whereupon the pin 10 representing the batter would be moved from the hole adjacent the home plate to the hole 8^a, representing the second base, and a new batter would take the batsman's place. The indicator piece would then be slid to the position over the section of the indicator bar marked "2" and the operation repeated. If, at this second spinning of the disk, the section marked TO43 should come beneath the pointer, it would indicate that the player marked 4 (that is, the catcher) had thrown the ball to the player marked 3, (3rd baseman) who had thereupon put out the runner in an attempt to steal 3rd base. This play would again cause the bases to be empty, and one man on the side to be out, which "out" would be indicated by the pointer, 14, 115 120 125 130

upon the dial, 12, and the sliding piece, 11, would be moved back over the division marked "0", and the play continued in the manner indicated until a complete game of base ball had been played.

5 Of course, the characters indicated in the sections of the circular divisions of the disk, may be varied considerably as desired, but the possible plays I have shown in Fig. 1, include, I believe, all those that occur in the game of base-ball as set forth in the official rules 10 of the game, and I have endeavored to make the distribution of said plays in accordance with the ordinary chances in a well played game of base-ball.

I remark that to cover the different possible plays it was necessary to bear in mind the fact (and to so indicate upon the disk) that certain plays may occur when certain of the bases are occupied that could not occur when other of the bases are occupied. For instance, the play ROF6 which is indicated in the circular division corresponding with the indicator division 20 "2", when second base is occupied and which indication ROF6 means "Runner obstructing fielder 6"; that is, the fielder, 6, (being the short stop) was obstructed by the runner on second base, cannot, of course, occur when the bases are unoccupied, and 25 therefore it would not be correct to have such an indication in the circular division opposite the "0" section of the indicator bar.

Having thus described my invention, I claim as new and desire to secure by Letters Patent:—

1. In a baseball game apparatus, the combination with a stationary bar having divisions respectively indicating the various positions of men on bases in the game of baseball, a movable member contiguous to said bar provided with divisions in line with and corresponding respectively to the divisions of said bar, said divisions of said movable member being laterally divided into sections, which sections have indicated thereon characters indicating the various plays in the game of baseball; together with the movable indicator piece carried by said bar, substantially as and for the purpose set forth. 35

2. In a baseball game apparatus the combination with a stationary bar having divisions respectively indicating the various positions of men on bases in the game of baseball, of the contiguous disk with respect to which said bar is radially disposed, said disk being provided with concentric 45 circular divisions in line with and corresponding respectively to the said divisions of said bar; which circular divisions are radially divided into sections, and which sections are provided with characters indicating the various plays in the game of baseball; together with the movable indicator piece carried by said bar, substantially as and for the purpose set forth. 50

In testimony whereof, I have hereunto affixed my signature.

IRVEN J. ROBERTS.
